United States Patent Office.

THOMAS DOLAN, OF PHILADELPHIA, PENNSYLVANIA.

Design No. 3,881, dated March 8, 1870.

DESIGN FOR A "BEDOUIN" OR "ARAB."

The Schedule referred to in these Letters Patent and making part of the same.

I, THOMAS DOLAN, of Philadelphia, county of Philadelphia, State of Pennsylvania, have invented or produced a Design for Part of an Arab or Bedouin, of which the following is a specification.

Nature of the Design.

My design relates to the peculiar fashioning of the rear of the shawl-like garments known as "Arabs" or "Bedouins," the design consisting of a hood-piece, in combination with gathered folds of the garment, as described hereafter, so as to impart to the rear of the same a peculiar and graceful appearance.

Description of the Accompanying Drawing.

Figure 1 represents a rear view of the "Arab" or "Bedouin" with my design as it appears when applied to the figure, and

Figure 2, a view, drawn to a reduced scale, of the "Arab" or "Bedouin" as it appears when unfolded.

General Description.

A, fig. 2, is a strip of any desired fabric, arranged as shown, and having, at the upper edge, a fold, *a*.

To the fabric, midway between its opposite ends, is stitched a hood-piece, *B*, of the form, or approximating to the form, represented in the drawing; and, where the lower pointed end of this hood is stitched

to the fabric, the latter is puckered or gathered, and thereby formed into a series of loose folds, *e e*, so that, when applied to the person, as shown in fig. 1, the rear of the garment will have the appearance shown in fig. 2.

The ornamentation of the garment may be varied without departing from the general character of the design; for instance, fringe may be stitched to the lower edge of the band *a*, and the ends and lower edge of the garment may have a similar fringe.

An ornamental tassel may also be hung at the point *x*, fig. 1, and at the point of the hood-piece *B*.

Irrespective, therefore, of any specific pattern of fabric, or any minor ornamentation of the garment,

I claim—

The design consisting of a hood-piece, *B*, in combination with the gathered folds *e e* of an "Arab" or "Bedouin," the whole being formed substantially as described.

In testimony whereof I have signed my name to this specification in the presence of two subscribing witnesses.

THOMAS DOLAN.
